SAFETY ROLLER MECHANISM FOR USE IN
WATCH MOVEMENT ESCAPES

Jason Glenn Bishop, Columbus, Ohio

Application July 22, 1949, Serial No. 106,148

5 Claims. (Cl. 58—122)

1

This invention relates to watch movements and, more particularly, to the escapement elements of such movements.

In standard watch movements, the intermittent release of an escapement wheel is effected by the engagement and disengagement of the peripheral teeth of the wheel with spaced stationary jewels provided on the yoke of an oscillating arbor-carried pallet lever. Timed rocking movement of the pallet lever is controlled by a collet 5 roller mounted on a staff about which a hairspring-actuated balance wheel oscillates, the roller or disk having a jewel projecting laterally from its periphery which engages with forked tines formed on the end of the pallet lever opposite to that engaged with the escapement wheel, whereby to enable the pallet lever to turn about its arbor to a degree regulated by spaced stationary banking stops or pins, to thereby release and lock in timed sequence the main spring-driven escapement wheel.

To prevent undesired movement of the pallet lever between its banking stops, particularly when the watch movement is subjected to shocks or jars, it is the present practice to provide the forked end of the pallet lever, that is, the end disposed adjacent to the balance wheel, with a rigid longitudinally projecting guard finger, the latter being disposed in a plane offset laterally to that of the pallet lever and spaced from the collet 30 roller jewel. The end of the guard finger is normally spaced from the peripheral surface of a safety roller, the latter being positioned on the balance wheel staff in spaced relation from the collet roller. The slight clearance provided between the outer end of the rigid guard finger and the peripheral surface of the safety roller is provided to avoid friction between relatively movable parts, but when the movement is jarred or shaken, any motion of the pallet lever away from an 40 associated banking pin or stop is arrested by direct contact of the outer end of the guard finger with the periphery of the safety roller. This roller, however, is formed with a peripheral recess or notch which enables the pallet lever to move freely without restraining action on the part of the safety roller when said lever at proper times is caused by the action of the lifting surfaces of the escapement wheel teeth to oscillate between the spaced banking pins.

The laterally offset guard finger on the pallet lever and its associated safety roller comprise devices which increase the thickness of a watch movement, and introduce mechanical complications, added costs and other undesirable conditions therein. Unless these parts bear a definite and predetermined relationship to each other at all times, mechanical difficulties are presented. Dust or foreign particles of matter offer obstructions and also if the cooperating parts should be

2

but slightly misaligned, a possible source of mechanical disorder is often presented.

It is an object of the invention to provide a mere efficient, simple and practical guard finger and safety roller construction for watch movements than has been hitherto employed in the art.

It is another object of the invention to provide an improved safety roller construction for watch movements, including a cooperative pallet lever-carried guard finger, in which the roller is formed with an arcuate guide, extending inwardly from its peripheral edge, for cooperation with the outer end of the guard finger.

It is a further object of the invention to provide a safety roller and guard finger construction in which a thin compact design is afforded well suited for modern watch construction.

It is another object of the invention to provide the escape movement of a watch to include a safety roller having guide surfaces formed thereon for engagement with a guard finger constituting an extension of an oscillatory pallet lever, and wherein the guide surfaces include merging circular and convolute regions which, while providing for close association of the guard finger with said surfaces, nevertheless permit of the required freedom of turning movement of the safety roller, in unison with the staff of the balance wheel, while the pallet lever is relatively stationarily positioned in engagement with one or the other of its banking stops.

Still another object of the invention is to provide a safety roller mechanism for watch movements characterized by its long life, structural simplicity and freedom from mechanical disorder.

For a further understanding of the invention, reference is to be had to the following description and the accompanying drawing, wherein:

Fig. 1 is a plan view, partly in horizontal section, of the escape mechanism of the watch movement formed in accordance with the present invention;

Fig. 2 is a similar fragmentary view disclosing the pallet lever and the safety roller of the escape mechanism in different positions of operation from those disclosed in Fig. 1;

Fig. 3 is a fragmentary vertical sectional view taken through the movement;

Fig. 4 is a plan view of a collet disk or roller formed in accordance with the present invention.

Referring more particularly to the drawings, the numeral 1 designates the escape wheel of a watch or other similar movement. The escape wheel includes the usual hub 2 which is secured to a rotatable mainspring-driven shaft 3. The wheel 1 is formed peripherally with the usual circumferentially spaced, tangentially extending teeth 4 having outer lifting surfaces 5.

Carried by the frame 6 of the movement is an arbor 7 upon which is mounted for oscillation

about the axis of the arbor a pallet lever 8. The lever at one end is formed with a yoke 9 which carries a pair of spaced pallet stones or jewels 10, the latter being provided with lifting surfaces 11 complementary to those of the teeth 4 of the escape wheel. The pallet lever is rocked at intervals by the lifting action of the surfaces 5 and 11 and its rocking action is confined, as usual, by means of banking stops or pins 12, which may be eccentrically mounted on set screw bases 12' carried by the movement frame.

The outer end of the pallet lever is formed with the usual fork 13 having spaced tines 14 formed with reversely beveled surfaces 15 for cooperation with a roller jewel 16 which projects rigidly and perpendicularly from a disk roller 17. The latter is mounted on the shoulder 17a of a collet hub 17b, which, in turn, is located on the staff 18 of a hairspring-actuated balance wheel 19, the ends of the staff being attenuated and supported in cap jewels 20 of the movement frame. The hair spring 19a has its inner end connected with the hub 20a and its outer end with the wheel 19. As the balance wheel oscillates about the longitudinal axis of the staff 18, the collet disk or roller 17 moves in unison therewith and likewise the roller jewel 16. This jewel is engaged first by one of the tines 14 and then the other, thus oscillating the collet roller 17 and the balance wheel 19 in accordance with the rocking action of the pallet lever 8.

In order to protect the pallet lever against accidental displacement, particularly when the movement is subjected to shock and jar, the present invention provides on one side of the forked end of the pallet lever an extending arm or guard finger 22, the outer end of said finger being formed to provide a lateral pin or stud 23. The stud is positioned normally in slightly spaced order from the circular peripheral surface 24 of the disk 17.

To provide for free oscillating movement of the pallet lever 8 and finger 22, when said pallet lever responds to the lifting action of the teeth 4 of the escape wheel, the disk or roller 17 includes an arcuate slot, groove or guide 26 which merges with the circular peripheral surface 24 of the disk. The guide 26 has as its center the pallet arbor 7. By reference to Fig. 1, it will be noted that the stud 23 of the spring arm is disposed at the inner end of the arcuate guide 26, a position which it occupies after the pallet lever has oscillated from the banking pin shown at the right of Fig. 1 to engagement with the banking pin shown at the left of Fig. 1.

On the oscillating return of the jewel 16 from the position which it occupies, as illustrated in Fig. 1, to the position shown in Fig. 2, the said jewel 16 is contacted by the pallet lever fork and thereby serving in a manner causing it to assume the operating position disclosed in Fig. 2. In this operation, the necessary movement of the pin or stud 23 takes place without friction, since the stud moves in and out of the groove or slot 26 and around the circular surface 24 of the roller 25, without contacting these surfaces unless the movement is jarred, and then the contact is but momentary.

With the construction described, the pallet lever is capably protected against jar and shock, and a simple and compact grouping of parts is provided adapted for thin watch construction. While the disk 17 has been shown as being separately formed from the shouldered hub 17b, these parts may be integrally formed, if desired. Other

mechanical changes of a similar nature may be made within the scope of the invention.

I claim:

1. In an escapement mechanism for watch movements, a mainspring-driven escape wheel, an oscillatory pallet lever formed at one end with a yoke having engagement with teeth provided on the periphery of the escape wheel, the opposite end of said lever being formed with spaced tines, spaced stationary banking stops limiting rocking movement of said pallet lever, a balance wheel staff, a circular disk roller movable in unison with said staff, a jewel pin on said roller arranged for alternate engagement with the tines of said pallet lever, said roller being formed with an arcuate guideway extending inwardly of the roller from its circular outer edge across one face of the roller to its central region about said staff, and a guard finger formed on the outer end of said pallet lever movable in said guideway during oscillation of said pallet lever between said banking stops.
2. In an escapement mechanism for watch movements, a mainspring-driven escape wheel, an oscillatory pallet lever formed at one end with a yoke having engagement with teeth provided on the periphery of the escape wheel, the opposite end of said lever being formed with spaced tines, spaced stationary banking stops limiting rocking movement of said pallet lever, a balance wheel staff, a circular disk roller movable in unison with said staff, a jewel pin on said roller arranged for alternate engagement with the tines of said pallet lever, said roller being formed with an arcuate guideway extending inwardly of the roller from its circular outer edge across one face of the roller to its central region about said staff, and a guard finger formed on the outer end of said pallet lever movable in said guideway during oscillation of said pallet lever between said banking stops, said finger being normally spaced from wall surfaces of said guideway when said pallet lever is in direct contact with one or the other of said banking stops.
3. In an escapement mechanism for watch movements, as defined in claim 1, and wherein said guard finger constitutes a continuation of one of the tines of said pallet lever.
4. In an escape mechanism for watch movements as defined in claim 1, and wherein the arcuate guideway on said disk roller is disposed in concentric relation to the axis of rocking movement of the pallet lever.
5. As a new article of manufacture, a disk roller for use in the escape mechanisms of watch movements, said roller including a circular body formed for axial connection with an associated oscillatory balance wheel staff, an arcuate guideway extending inwardly of the roller from a circular outer edge across one face of the roller to the central region thereof about said staff, and a pallet lever engaging jewel pin projecting perpendicularly from a face of said roller body in which the guideway is formed.

65 JASON GLENN BISHOP.
